(57) **CLAIM**

The ornamental design for a magnetic wireless charger, as shown and described.

DESCRIPTION

FIG. 1 is a front, left and top perspective view of a magnetic wireless charger, showing my design.

FIG. 2 is a front, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1; and,

FIG. 10 is another front, right and bottom perspective view thereof, shown in another configuration.

Throughout the views, the cable portion of the magnetic wireless charger is shown with a symbolic break in its length. The appearance of any portion of the article between the break lines forms no part of the claimed design.
